FIG. 5.

UNITED STATES PATENT OFFICE.

JAMES A. HORNE, OF DENVER, COLORADO.

AEROPLANE.

1,300,969.

Specification of Letters Patent. Patented Apr. 15, 1919.

Application filed April 26, 1917. Serial No. 164,697.

To all whom it may concern:

Be it known that I, JAMES A. HORNE, a citizen of the United States, residing at Denver, in the county of Denver and State 5 of Colorado, have invented certain new and useful Improvements in Aeroplanes, of which the following is a specification.

My invention relates to new and useful improvements in aeroplanes and more particularly in aeroplanes of the biplane type, 10 the primary object of my invention being the provision of a novel form of propelling mechanism and a novel and more efficient system of controlling the propellers and the 15 transmission of power thereto.

In this connection, one of the main features of my invention resides in the provision of bucket-like propellers arranged in pairs, one at either side of the main body of 20 the aeroplane, and in the provision of means for controlling transmission of power to the propellers so that both pairs may be driven simultaneously, under normal conditions, or either pair may be driven while the other 25 pair remains idle.

A still further object of my invention resides in constructing an aeroplane having a pair of main supporting planes and a pair of balancing or equalizing planes, and in 30 mounting both sets of planes so that they may be angularly adjusted, both sets being arranged and controlled for simultaneous and corresponding tilting movement.

In this connection, a still further object 35 of my invention consists in providing an improved body design or structure for supporting the power unit, propelling mechanism and operator which also supports both sets of planes and which is so arranged as to 40 permit their being tilted in any desired manner.

With these and other objects in view, my invention will be more fully described, illustrated in the accompanying drawings, and 45 then specifically pointed out in the claims which are attached to and form a part of this application.

In the drawings:

Figure 1 is a perspective view of my im- 50 proved aeroplane;

Fig. 2 is a longitudinal sectional view, showing certain features in the controlling mechanism of the propellers;

Fig. 2^a is a fragmentary view correspond- 55 ing to Fig. 2, illustrating the controlling

mechanism by means of which the planes are tilted;

Fig. 3 is a transverse sectional view looking rearwardly and showing the propelling mechanism and its controlling system in elevation;

Fig. 4 is a plan view of the aeroplane;

Fig. 5 is a fragmentary view partially in plan and partially in section, illustrating the controlling means for the power transmission;

Fig. 6 is a similar view, showing a modified form of controlling means.

Corresponding and like parts are referred to in the following description and indicated 70 in all the views of the drawings by the same reference characters.

My improved aeroplane includes a main body or frame 10 built up of pipe or rod sections in the manner best shown in Fig. 1. 75 This main frame includes a number of diamond shaped frame sections 11 disposed with their major axes in a common horizontal plane and their minor axes in a common vertical plane, these sections being preferably symmetrically spaced from each other and held in such spaced relation by connecting frame sections 12 joining the upper vertices of the adjacent sections and corresponding sections 13 joining the lower vertices of adjacent sections 11. Each of the sections 11 is further braced by intersecting diagonal braces 14 which, at their point of intersection, join to a hub 15.

The vertically disposed braces 14 are extended below the main frame 10, as shown at 90 16, and bent outwardly laterally to form spindles for a pair of forward ground engaging wheels 17. Lower frame members 18 are connected to the lower end portions of 95 the extensions 16 and at their forward ends are curved upwardly and rearwardly to provide bumpers or runners 19 and at their rear ends project horizontally and have laterally offset spindles to receive rear ground 100 engaging wheels 20. These rearward extensions 18 are suitably braced by transverse brace elements 21 and are also braced to the main frame sections 11 by diagonal braces 22 so that the lower frame section, together 105 with the supporting wheels provide a suitable support for the aeroplane when it is at rest upon the ground and also facilitate its starting and alighting.

The forward ends or vertices of the frame 110

- sections 11 are formed to provide alined hubs 23 which receive a plane supporting shaft 24 which is held against movement in the hubs by set bolts 25. In like manner, 5 the rear ends or vertices of the frame sections 11 are formed to provide alined hubs 26 which receive the main or supporting plane carrying shaft 27 which is held against movement in the hubs by set bolts 28.
- 10 These shafts are parallel to each other and horizontally disposed, the rear shaft which carries the main supporting planes being of considerably greater length than the forward shaft which carries equalizing or balancing planes. Of course, the opposite ends of each shaft project an equal distance beyond the outermost of the frame sections 11, 15 as will be clearly noted by reference to Fig. 4 of the drawings.
- 20 Upper and lower rectangular shaped balancing planes 29 have their end frame members connected by vertical braces or struts 30 and by diagonally disposed braces 31 which, at their intersections, are formed to provide hubs 32 which are journaled upon the ends of the shaft 24. The forward and rear edges of these planes may be braced or stiffened by vertically disposed struts 33, 25 together with guy wires 34, in the usual or any preferred manner. In like manner, the main supporting planes 35 are braced and held in spaced relation at their corners by vertical struts 36 and by diagonal braces 37 formed to provide hubs 38 rotatably journaled upon the ends of the shaft 27. Stop 30 collars 39 and 40 may be applied to the shafts 24 and 27, respectively, to hold the planes against other than turning movement about the shafts. Furthermore, the 40 main planes at their front and rear edges may be braced with struts 41 and wire braces 42 in the same manner as the planes 29.
- 45 Tail supporting frame members 43 extend rearwardly from the main frame 10 and support the usual or any preferred form of tail 44 which, at its rear end, carries a vertically disposed rudder 45 and a horizontally disposed rudder 46, the former 50 of which serves to direct the movement of the aeroplane to the right or left and the latter of which assists in causing upward or downward movement of the aeroplane at the will of the operator.
- 55 A hand lever 47 is pivoted intermediate its length upon a suitable bracket carried by one of the diagonal braces 14 of the frame member and operates with a notched segment 48 engageable by the pawl of a hand latch 49. A cord, cable or wire 50 is fixed to the hand lever at a point above its point of pivotal support and at one end extends forwardly and is passed upwardly about a pulley 51 supported by one of the 60 forward braces 14 and is secured to the rear edge of the upper balancing plane 29. The opposite end of this cable extends rearwardly, is passed downwardly about a pulley 52, and is secured to the rear edge of the lower main supporting plane 35. In like manner, a second cord, cable or wire 53 is secured to the lower or free end of the hand lever 47 and has one end passed forwardly about a pulley 54 disposed adjacent the pulley 51 and downwardly and secured 70 to the rear edge of the lower balancing plane 29. The opposite end of this latter cord or cable is extended rearwardly and upwardly about a pulley 55 located adjacent the pulley 52 and is secured to the rear edge of the upper supporting plane 35. Under these circumstances, it will be clear that rearward swinging of the hand lever 47 from its intermediate vertical position shown will act through the cables 50 and 53 to cause upward tilting of the forward edges of all of the planes, each pair of planes, with its braces, turning about its supporting shaft to any desired extent depending upon the amount of movement of the lever. In like manner, movement of the lever in the opposite direction will cause downward tilting of the forward edges of the planes and upward tilting of the rear edges.
- 80 A second hand lever 56 is pivoted intermediate its length to coöperate with a notched segment the same as the lever 47 and a cord, cable or wire 57 is connected at one end to the lower free end of this lever and at its opposite end to the forward corner of the left hand side of the horizontal rudder 46. A similar cord or cable 58 is connected to the lever 56 a distance above its point of pivotal support equal to the distance between such point of support and 90 its free end and at its other end is connected to the forward edge of the right hand corner of the rudder 46. A cord, cable or wire 59 is connected to the free end of the lever 47 and to the upper forward corner 100 of the rudder 45 and a similar cable 60 is connected to the lever 47 above its point of pivotal support and to the lower forward corner of the rudder 45. The two rudders 45 and 46 are secured to the rear end of the 105 tail by a ball and socket joint 61 and it will, therefore, be apparent that forward swinging of the lever 56 will exert strain upon the cord 57 and correspondingly slacken the cord 58 so that the two rudders as a whole 110 will be swung toward the left, while reverse swinging of the lever 56 will swing the rudders to the right to correspondingly direct the aeroplane. Furthermore, if the hand lever 49 is swung forwardly, to tilt 115 the planes downwardly, it will tighten upon the cord 60 and slacken upon the cord 59 to cause downward tilting of the combined rudders, which will assist in directing the aeroplane downwardly, while if the lever 120
- 130

the aeroplane opposite the direction in which he wishes to turn, but may also operate the rudder to assist in the turning.

If, during its course, the aeroplane should

- 5 start to tilt transversely, the natural result would be that the operator would lean toward the higher side of the aeroplane and having his hands upon the wheel would turn it in that direction. As a consequence, this 10 turning of the wheel would release the clutch through which power is transmitted to the propellers at the high side of the aeroplane while leaving the other clutch in active position to transmit power to the 15 propellers at the low side, so that these propellers could act to bring the aeroplane to a level position again. It will, of course, be apparent that this form of control is absolutely automatic, assuming that the driver 20 has his hands upon the wheel. In like manner, if the lever form of control shown in Fig. 6 is employed, if the operator has his hands upon the levers 103, any tilting movement of the aeroplane will naturally cause 25 him to pull the proper lever in the proper direction to cut out transmission of power to one set of propellers or the other which will bring the aeroplane again to level position. If, at any time, the operator or driver 30 wishes to stop the propellers, without stopping his engine, such as would be the case in descending, he may do this by merely pressing against the wheel 99 to move the column longitudinally through its bearings 35 and thus releasing both clutches, or if the lever control is employed he may do it by swinging the lever 106 to the right.

From the foregoing description, it will be apparent that both the main supporting 40 planes, the equalizing planes, and the rudder operate together to determine whether the aeroplane shall follow an ascending or descending course and that both the rudder and the propellers operate in conjunction 45 to determine the lateral direction of travel and to balance the machine against lateral tilting, as well as to cause proper lateral tilting of the machine when turning a curve.

The control mechanism for these various 50 elements are all arranged to be operated by natural movements of the driver, under the various conditions existing so that the control is to all intents and purposes automatic.

55 Although I have illustrated and described my invention in all its details of construction, it will of course be understood that I do not wish to limit myself to such details, but reserve the right to make any changes, 60 within the scope of the appended claims, without departing from the spirit of my invention.

Having thus described the invention, what is claimed as new is:

- 65 1. In an aeroplane, a frame, planes car-

ried by the frame, a pair of propeller buckets supported by the frame, one pair at either side of the longitudinal center of the frame, each pair of buckets being supported for simultaneous rotary movement 70 about a propeller shaft located between them and to which they are connected and also for simultaneous turning movement about an axis parallel to such shaft to always present their open face in the same direction, 75 means for transmitting power to the propeller shafts to drive the buckets, and a single controlling means for selectively cutting off the supply of power to either pair of buckets or to both pairs. 80

2. In an aeroplane, a frame, a pair of propeller shafts journaled in the frame, one at either side of the longitudinal center thereof, a pair of propellers supported by each shaft to be rotated thereby, a compound 85 drive shaft including aligned intermediate and terminal sections, means for transmitting power from the intermediate to the terminal sections, means for transmitting power from the terminal sections to the respective propeller shafts, and a single controlling means for preventing transmission 90 of power from the intermediate section to either one or both of the terminal sections.

3. In an aeroplane, a frame, a pair of propeller shafts journaled in the frame, one at either side of the longitudinal center thereof, a pair of propeller buckets supported by each shaft to be rotated thereby, a compound 100 drive shaft including intermediate and terminal sections, means for transmitting power from the intermediate to the terminal sections, means for transmitting power from the terminal sections to the propeller shafts, and means for preventing transmission of 105 power from the intermediate section to either one or both of the terminal sections, said means including clutches controlling the transmission of power from the intermediate to the terminal sections, shipper 110 levers operatively engaging the clutches, a column having a hand wheel, and a rocker member fixed to the column and having arms projecting in juxtaposition to the shipper levers whereby turning of the column in one 115 direction will act through the rocker member to engage one shipper lever and turning in the other direction will act through the rocker lever to engage the other shipper lever. 120

4. In an aeroplane, a frame, a pair of propeller shafts journaled in the frame, one at either side of the longitudinal center thereof, a pair of propeller buckets supported by each shaft to be rotated thereby, a compound 125 drive shaft including intermediate and terminal sections, means for transmitting power from the intermediate to the terminal sections, means for transmitting power from the terminal sections to the propeller shafts, 130

and means for preventing transmission of power from the intermediate section to either one or both of the terminal sections, said means including clutches controlling the transmission of power from the intermediate to the terminal sections, shipper levers operatively engaging the clutches, a column having a hand wheel, and a rocker member fixed to the column and having arms projecting in juxtaposition to the shipper levers whereby turning of the column in one direction will act through the rocker member to engage one shipper lever and turning in the other direction will act through the rocker member to engage the other shipper lever, the column being movable under pressure exerted upon the hand lever to bring the rocker member into simultaneous engagement with both shipper levers to cause freeing of both clutches.

5. In an aeroplane, a pair of propeller shafts supported for rotary movement, a pair of arms extending diametrically from

each propeller shaft adjacent each end, pivot shafts journaled in the free ends of the arms, 25 propeller buckets fixed to the pivot shafts to turn therewith, compound gear elements loosely mounted on the propeller shafts, driving means between each compound gear element and the adjacent shafts whereby the 30 pivot shafts and their buckets will have a turning movement proportioned to but distinct from the turning movement imparted to them by the propeller shafts, a compound drive shaft including an intermediate and 35 terminal sections, means for imparting power from the terminal sections to the propeller shafts and from the terminal sections to the compound gear elements, means for applying power to the intermediate section, 40 and means for selectively locking both, either or neither of the terminal sections to the intermediate section.

In testimony whereof I affix my signature.

JAMES A. HORNE. [L. S.]
